UNITED STATES PATENT OFFICE.

JOSEPH HAMILTON, OF PHILADELPHIA, PENNSYLVANIA, ASSIGNOR TO
JAMES DUNLAP CARPET COMPANY, OF PHILADELPHIA, PENNSYLVANIA, A CORPORATION OF PENNSYLVANIA.

YARN-PRINTING MACHINE.

SPECIFICATION forming part of Letters Patent No. 699,948, dated May 13, 1902.

Application filed April 18, 1901. Serial No. 56,349. (No model.)

To all whom it may concern:

Be it known that I, JOSEPH HAMILTON, a citizen of the United States, residing at the city of Philadelphia, State of Pennsylvania, have 5 invented certain new and useful Improvements in Yarn-Printing Machines, of which the following is a full, clear, and exact description, reference being had to the accompanying drawings, forming a part of this specification.

This invention relates to that class of yarn-printing machines in which the yarn to be printed is wound upon an intermittently-rotatable drum and in which a color-containing 15 box provided with a color-applying wheel and oppositely-disposed rubbing devices is carried back and forth beneath and parallel to the axis of the drum in such manner that the said wheel will apply longitudinal ridges 20 or stripes of color to the opposing yarn and the rubbing devices will, at the end of each stroke of the color-box, be moved into and out of operative position relatively to the yarn in alternate succession, so as to act alternately 25 upon the successive ridges or stripes of color applied to the yarn.

My invention resides especially in a novel construction and organization of rubbing devices and of the controlling mechanism therefor whereby a uniform and effective rubbing and distribution of the ridges or stripes of color upon the yarn are attained, as will be hereinafter particularly described and claimed.

In the drawings, Figure 1 is an elevation 35 of a portion of a yarn-printing machine in which my invention is embodied. Fig. 2 is a longitudinal section through the trackway, showing the mechanism for controlling the active and idle positions of the rubbing devices. Fig. 3 is a transverse section as on the line xx of Fig. 2. Fig. 4 is a sectional elevation of the color-box, its carriage, and the rubbing devices, showing a portion of the trackway for said carriage and one end of 40 the bar for controlling the positions of the rubbing devices. Fig. 5 is a transverse vertical section as on the line yy of Fig. 4.

A represents the drum, upon which is wound the yarn to be printed; B, a trackway ar-

ranged beneath and parallel to the axis of 50 the drum; C, a carriage provided with wheels c , which bear upon the rails of the trackway, and c' a band connected at its extremities with the carriage and passed around pulleys $c^2 c^3$, driven by suitable mechanism to effect 55 the traverse of the carriage back and forth on the trackway. Upon the carriage is detachably supported the color-containing box D, which includes in its construction a supply-wheel d , adapted during the traverse of 60 the carriage beneath the drum to roll against the opposing yarn and apply ridges or stripes of color thereto.

The parts above mentioned require no detailed description herein, as they are of well-known construction and operation.

Supported in bearings at the respective ends of the carriage are vertically-movable posts 1, which are provided on their lower ends with lugs 2 and are maintained yieldingly depressed by the action of encircling springs 3, interposed between the respective lugs and the under side of the carriage. To each of the lugs is pivoted a depending slotted roller-bearing 4, equipped with an anti-friction-roller 5. The said pivotally-mounted bearing 4 is maintained in vertical position normally by gravity. While freely movable toward the body of the carriage, the said pivoted bearing is prevented from swinging 80 rearward beyond the vertical by a suitably-disposed stop 6 thereon abutting against the opposing edge of the lug.

The upper end of the post 1 is socketed to receive a telescopic or independently-movable stem 8, which is maintained normally raised by the action thereagainst of a spring 9, confined within the socket. A lateral pin 10 on the stem extends through a vertical slot 11 in the post and prevents rotation of the stem. 85 On the stem is formed or secured an L-shaped bracket 12, to the upwardly-projecting limb of which is pivotally connected an outwardly-projecting link, one arm, 13, of which has an upper rounded or inclined surface, and the other arm, 14, extends over the horizontal limb of the bracket and carries a pin 15, that depends through an orifice in such member.

Encircling this pin is a spring 16, which, bearing against the arm and against a washer 17, imposed on the bracket 12, tends to yieldingly maintain the link-arm 13 in a normal or raised position. The two oppositely-disposed links face outwardly on their respective bracket-supports. Hence the rounded surfaces of their arms 13 incline outwardly from the color-box D, and they are arranged in such horizontal planular relation thereto that while their bearings are in longitudinal alinement with the color-wheel their upper surfaces are normally below the plane of the periphery of the color-wheel.

15 Between the rails and parallel therewith is supported a bar 18, which is movable vertically into and from the path traversed by the pivotally-supported rollers 5 during the reciprocation of the carriage. The ends of the 20 bar are preferably beveled, as indicated, to facilitate the passage thereon of said rollers. This bar is supported horizontally upon a series of upwardly-inclined arms 19, carried by rock-shafts 20, having their bearings in the 25 rails of the trackway. The arms are preferably provided with antifriction-rollers 21 for the support of the bar. Depending from the ends of the rock-shafts are arms 20^a, which are united by means of links 22, so as to be 30 movable as a unit. One of these latter arms is connected with a part of the main frame by means of a strong retracting-spring 23, which tends to turn the rock-shafts in a manner to maintain the arms 20 and, perforce, the bar 18 normally elevated. One of the arms 20^a is 35 also connected, by means of a link 24, with a treadle 25, whereby when the latter is depressed (by the foot of the operator) the respective arms will be moved against the action 40 of the spring to effect the lowering of the bar 18.

From the foregoing it will be seen that the bar 18 is maintained normally raised and that during the movement of the carriage in either 45 direction the depending pivotally-mounted roller 5 of the forward or leading rubbing device will abut against and ride idly upon the bar. It will also be seen that the wheel of the traveling color-box will apply a ridge or 50 stripe of color to that part of the yarn against which the wheel rolls and that the roller 5 of the rearward rubbing device will bear against and along the opposing bar and be forcibly raised thereby in a manner to elevate against 55 the compression of the spring 3 the post 1 and its appurtenances, including the link 13 14, causing the rounded arm 13 of the latter to bear against the yarn and rub along and distribute the ridge of stripe being applied by 60 the color-wheel until the roller 5 escapes the bar at the end of the stroke of the carriage, whereupon described supporting actuating mechanisms of the rubbing device will resume their normal position. In view of the 65 independent vertical movement of the stem 8, as well as the independent rocking movement of the spring-actuated link within its

bracket-bearing 12, the rounded arm of said link will be caused to press yieldingly against and accommodate itself to any irregularities 70 or variations in the strands of yarn, thus insuring a uniform and effective rubbing action. In the next succeeding stroke of the carriage the then leading rubber will be moved into action by its engagement with the opposing 75 bar. Thus at the end of each stroke of the carriage the rubbing devices will be moved into and out of operation relatively to the yarn in alternate succession, so as to act alternately upon the successive ridges or stripes applied 80 to the yarn by the rotating color-wheel.

If it be desired to apply the ridges or stripes of color without spreading or rubbing the same, the bar 18 is depressed by the operator preparatory to and during the stroke of the 85 carriage, in which case the rubbing devices travel idly below the yarn on the drum.

Having thus described my invention, what I claim as new, and desire to secure by Letters Patent, is—

90 1. In a yarn-printing machine, the combination with the yarn-drum, the carriage, the color-box and its wheel, and the rubbing devices on the respective ends of the carriage, of a horizontally-disposed bar, upwardly-inclined arms supporting said bar, rock-shafts carrying said arms, other arms extending downwardly from said rock-shafts, and links uniting said last-mentioned arms to cause them to operate as a unit; devices operating 100 to maintain the horizontal bar normally elevated, and means to effect an opposite lowering movement of said bar when desired.

105 2. The combination with the yarn-drum, the carriage, the color-box and its wheel, of the rubbing devices at the respective ends of the carriage, said devices comprising each a vertically-movable support, a spring-controlled link pivotally mounted in an independent bearing at the upper end of said support, operating to maintain the same yieldingly in position, springs to maintain said supports in normal position, a roller, a slotted bearing therefor pivotally mounted on the lower end of said support, a horizontally-115 arranged lifting-bar having an inclined end, with actuating means operated by a treadle to bring said bar into the path of said roller; substantially as described.

110 3. The combination with the yarn-drum, the carriage, the color-box and its wheel, of the rubbing devices at the respective ends of the carriage, said devices comprising each a vertically-movable post, means to maintain it in 115 normal position, a stem independently movable on said post, a spring to maintain said stem normally raised, a spring-controlled link pivotally mounted on said stem, together with means for bodily raising the said post with its connections, substantially as described.

120 4. The combination with a yarn-drum, the carriage, the color-box, the color-wheel, the rubbing devices on the opposite ends of said

carriage, means to yieldingly support each rubbing device in an independently-movable post, spring devices to maintain the said post in normal position, and means to raise said 5 post against counter spring action; substantially as described.

In testimony whereof I have hereunto af-

fixed my signature this 13th day of April, A. D. 1901.

JOSEPH HAMILTON.
